2 Sheets-Sheet 2

INVENTOR:
Howard Logan
By G. A. Bragg, Atty.

UNITED STATES PATENT OFFICE.

HOWARD LOGAN, OF CHICAGO, ILLINOIS.

TANK.

Application filed April 1, 1922. Serial No. 548,860.

To all whom it may concern:

Be it known that I, HOWARD LOGAN, citizen of the United States, residing at Chicago, in the county of Cook and State of Illinois, have invented a certain new and useful Improvement in Tanks, of which the following is a full, clear, concise, and exact description.

My invention relates to tanks and is of particular service when employed in connection with the tanks of tank cars, though the invention is not to be thus restricted.

My invention resides in providing a closure for the tank outlet opening and in threaded engagement with the tank, this closure being formed for turning engagement upon its interior and exterior, the interior formation being accessible when the closure is in place.

In the preferred embodiment of my invention the tank is formed with a circular discharge opening and is provided with a removable plug within said opening and in threaded engagement with the surrounding portion of the tank and having an exterior formation whereby it may be turned and an interior formation whereby it may also be turned.

In the preferred embodiment of the invention there is a stem which projects from an inner portion of the plug through the side of the tank opposite the side where the plug is located to be operable upon the exterior of the tank. Means are also preferably furnished for obstructing movement of the stem longitudinally of its axis and serving to hold the inner end of the stem at the plug opening in position to enable the plug to be engaged with the stem in the entering movement of the plug, in case the plug and stem are separable.

In order that the contents of the tank may be directed in its flow therefrom, I provide a discharge nozzle in register with the discharge opening. This discharge nozzle desirably includes an angular outlet portion and may be formed with an opening through which the exterior of the plug may be engaged for turning it. In order that the discharge nozzle may not be liable to receive violent blows while the tank or tank car is in transit, the nozzle is made removable to be assembled with the balance of the structure

when the tank or tank car has reached destination.

Before the tank is to be filled with the contents to be stored therein for shipment or other purpose, the plug may be placed in tank closing position by turning it either from the interior or the exterior. When the contents of the tank are to be removed the plug is loosened from the tank interior sufficiently to enable it to be finally removed by turning it from the interior of the tank to prevent the released contents from spilling upon the person engaged in removing the plug. By so constructing the plug that it may be turned both from the interior and exterior of the tank the long stem or other tool that finally completes the removal of the plug from or through the interior of the tank is relieved of the severe strain which is usually required to start the plug, it being possible to employ a sufficiently short and stout tool to perform the latter function upon the tank interior.

The invention will be fully explained by reference to the accompanying drawings in which Fig. 1 is a longitudinal sectional elevation of an intermediate portion of a tank car constructed in accordance with one embodiment of the invention; Fig. 2 is a sectional view, on a larger scale, on line 2-2 of Fig. 1, with the discharge nozzle and other parts removed and parts broken away; Fig. 3 is a view on a larger scale mainly in section on line 3-3 of Fig. 1; Fig. 4 is a longitudinal sectional elevation of an intermediate portion of a tank car constructed in accordance with another embodiment of the invention; Fig. 5 is a sectional view on a larger scale on line 5-5 of Fig. 4, with its discharge nozzle portion and other parts removed; Fig. 6 is a sectional view on line 6-6 of Fig. 7; and Fig. 7 is a view on a larger scale mainly in section on line 7-7 of Fig. 4.

Like parts are indicated by similar characters of reference throughout the different figures.

The invention is shown as being embraced in a tank car structure, the tank 1 being supported upon the tank car center sills 2 in any suitable or well known way. The tank is formed with a circular discharge opening 3 in its bottom side, this opening being pref-

erably formed in a fitting 4 which is riveted upon and beneath the bottom of the tank. A removable plug 5 is receivable in the opening 3, it being adapted for threaded engagement with the surrounding portion of the tank part 4. This plug has an exterior formation 6 whereby it may be turned from the exterior of the tank. This formation 6 may be of any suitable nature. In the embodiments of the invention illustrated it is short and polygonal in contour whereby it may be engaged by a suitable form of wrench. The plug is provided with an interior formation whereby it may be turned by means of force applied thereto upon its inner side. The plug is preferably formed with a socket 7 upon its inner side, this socket being polygonal in contour to receive a stem 8 whose plug engaging lower end is also polygonal in contour and conforms in shape to the socket, this construction permitting the plug and its stem to be in separable relation although the invention is not to be thus limited.

25 The stem is desirably provided with means for obstructing movement thereof longitudinally of its axis whereby the inner or lower end of the stem may be maintained at the plug opening in position to enable the plug to be engaged with the stem in the entering movement of the plug so that the closing movement of the plug may be finished, if desired by turning the plug stem and whereby ample engagement is afforded between the plug and stem when the stem is employed to complete the removal of the plug.

30 The means for obstructing the movement of the stem longitudinally of its axis may reside in a collar 9 fixed upon the stem and engaging the under side of the top of the tank and a collar 10 fixed upon the stem and engaging the upper end of the bearing 11 that is upon the top side of the tank dome 12. There is desirably no appreciable lost

35 motion between the collars and the portions of the tank structure that are located between the collars so that the stem is confined to a substantially fixed zone of rotation.

40 The upper end of the stem may be polygonal in contour according to the construction of Figs. 1 and 2 whereby a suitable wrench may be engaged therewith. In order to prevent tampering, the upper end of the stem may be enclosed by means of a cap 13 in hinged connection with an extended part of the bearing 11, a seal 14 guarding against undetectable opening of this closure.

45 In the embodiment of the invention shown in Fig. 4, the upper end of the stem, although projecting through the tank 1, terminates within the tank dome 12 and is provided with a crank 15 whereby the stem may be turned. In this embodiment of the

invention movement of the stem longitudinally of its axis is guarded against by means of collars 9 and 16 fixed upon the stem and in close engagement with the top portion of the tank that is interposed between these collars. By means of the collars 9 and 10 in the structure of Fig. 1 and the collars 9 and 16 in the structure of Fig. 4 the inner or lower end of the stem is held at the plug opening in position to enable the plug to be engaged with the stem in the entering movement of the plug.

50 In order that the contents of the tank may be suitably directed in their outward flow I provide a discharge nozzle 17 upon the exterior of the tank and in register with the discharge opening 3. This nozzle is desirably in separable relation with the tank either by having its upper end in threaded engagement with the fitting 4 according to the structure of Figs. 1, 2 and 3 or by means 55 of the clamping bolts 18 pivoted upon the bottom side of the fitting 4 and having their nuts 19 engageable beneath the ears 20 that project laterally from the nozzle and which are provided in pairs, the ears of each pair 60 being separated to receive the bolts therebetween, as illustrated in Figs. 4 and 7. In this latter construction the top of the nozzle may be provided with a packing gasket 21 adapted for fluid tight abutting engagement 65 with the rim 22 of the fitting 4.

When the tank is a part of a tank car the nozzle 17 passes between the car center sills 2. The angular extension 23 may be in the nature of a separate pipe screwed into place 100 and underlying one of the center sills. This extension may be equipped with a gate valve 24 for controlling the outward flow of fluid. A delivery hose 25 may be clamped upon the outer end of the extension 23 if desired. The 105 main portion of the nozzle that extends between the center sills is downwardly continued below its angular branch 23 to form a pocket 26 for holding the plug 5 when the unscrewing movement of the plug has been applied by its stem 8. In the form of the invention illustrated in Fig. 3, there is a T 110 27 that establishes connection between and forms parts of the upright and angular portions of the nozzle. This T has an opening 115 in its lower end that is normally closed by a cap 28. A nozzle thus constructed may be screwed into place before the plug 5 is initially loosened to prepare for its removal by the operation of the plug stem 8 since the 120 cap 28 may be removed to permit the passage of a wrench through the upright portion of the nozzle into engagement with the outer end of the plug 5 to loosen the same to permit further turning of the plug by its 125 stem 8 without undue tortional strain upon the stem.

In the structure of Fig. 3, after the plug

has been initially loosened the cap 28 is re-applied to restore the nozzle to its normal shape, the plug being caught by the cap when the plug is completely removed. Thus 5 the tank may readily be opened at its discharge outlet without danger of having its contents spilled upon the person opening the tank and without requiring the exertion of undue effort upon the plug stem. When 10 the contents of the tank have been withdrawn the nozzle may, if desired, be removed. When inverted, after its removal, the plug will fall out of the nozzle and may readily be screwed into the bottom of the 15 tank to prepare the tank for the reception of fresh contents.

In the structure of Fig. 7 there is no closure corresponding to the closure 28 of the structure of Fig. 3, making it desirable to 20 initially loosen the plug before the nozzle is applied.

If it should be desired to retain the nozzle in assembly with the tank of the tank car it may be weakened as indicated at 29 for 25 the purpose of causing the nozzle to be broken at this place if the lower part thereof should be violently struck, to prevent the distortion of the tank bottom.

While I have herein shown and particularly 30 described the preferred embodiment of my invention I do not wish to be limited to the precise details of construction shown as changes may readily be made without departing from the spirit of my invention, 35 but having thus described my invention I claim as new and desire to secure by Letters Patent the following:—

1. A tank having a circular discharge 40 opening; a removable plug within said opening and in threaded engagement with the surrounding portion of the tank and having an exterior formation whereby it may be turned; a stem within the tank and in separable turning engagement with said 45 plug; and means for obstructing movement of the stem longitudinally of its axis and serving to hold the inner end of the stem at the plug opening in position to enable the plug to be engaged with the stem in the entering movement of the plug.

2. A tank having a circular discharge 50 opening; a removable plug within said opening and in threaded engagement with the surrounding portion of the tank and having an exterior formation whereby it may be turned; a stem in separable turning engagement with an inner portion of the plug through the side of the tank opposite the side where the plug is located to be operable upon the exterior of the tank; and means for obstructing movement of the stem longitudinally of its axis and serving to hold the inner end of the stem at the plug opening in position to enable the plug to be engaged

with the stem in the entering movement of 65 the plug.

3. A tank having a circular discharge 70 opening, a removable plug within said opening and in threaded engagement with the surrounding portion of the tank and having an exterior formation whereby it may be turned and an interior formation, accessible when the plug is in place, whereby it may also be turned; and a discharge 75 nozzle upon the exterior of the tank and in register with said discharge opening and having an angular outlet portion, said nozzle having an opening through which said plug is accessible.

4. A tank having a circular discharge 80 opening; a removable plug within said opening and in threaded engagement with the surrounding portion of the tank and having an exterior formation whereby it may be turned; a stem within the tank and in turning relation to said plug; and a discharge nozzle upon the exterior of the tank and in register with said discharge opening and having an angular outlet portion, 85 said nozzle having an opening through which said plug is accessible.

5. A tank having a circular discharge 90 opening; a removable plug within said opening and in threaded engagement with the surrounding portion of the tank and having an exterior formation whereby it may be turned; a stem in turning relation to and projecting from an inner portion of the plug through the side of the tank opposite the side where the plug is located to be operable upon the exterior of the tank; and a discharge nozzle upon the exterior of the tank and in register with said discharge opening and having an angular outlet portion, 95 said nozzle having an opening through which said plug is accessible.

6. A tank having a circular discharge 100 opening; a removable plug within said opening and in threaded engagement with the surrounding portion of the tank and having an exterior formation whereby it may be turned; a stem within the tank and in separable turning engagement with said plug; and a discharge nozzle upon the exterior of the tank and in register with said discharge opening and having an angular outlet portion, 105 said nozzle having an opening through which said plug is accessible.

7. A tank having a circular discharge 110 opening; a removable plug within said opening and in threaded engagement with the surrounding portion of the tank and having an exterior formation whereby it may be turned; a stem in separable turning engagement with an inner portion of the plug through the side of the tank opposite the side where the plug is located to be oper-

posite the side where the plug is located to be operable upon the exterior of the tank; means for obstructing movement of the stem longitudinally of its axis and serving 5 to hold the inner end of the stem at the plug opening in position to enable the plug to be engaged with the stem in the entering move- ment of the plug; and a discharge nozzle separably assembled with the tank and in register with said discharge opening and 10 having an angular outlet portion.

In witness whereof, I hereunto subscribe my name this 20th day of March A. D., 1922.

HOWARD LOGAN.
